M. A. Laughridge ATTORNEY

UNITED STATES PATENT OFFICE.

EDWARD ALLEN EVERETT, OF LONG ISLAND CITY, NEW YORK.

LIGHTNING-ARRESTER.

1,401,596

Specification of Letters Patent. Patented Dec. 27, 1921.

Application filed September 15, 1920. Serial No. 410,523.

To all whom it may concern:

Be it known that I, EDWARD ALLEN EVERETT, a citizen of the United States, and a resident of Long Island City, in the county 5 of Queens and State of New York, have invented certain new and useful Improvements in Lightning-Arresters, of which the following is a specification.

This invention relates to lightning arresters such as are used on telegraph lines 10 and has for an object to provide a device of this kind which is simple in construction and cannot get out of order, and which is easily adjusted. These objects are obtained 15 by the construction described in the following specification and shown in the accompanying drawing in which Figure 1 is a side elevation of the arrester in place, Fig. 2 is a plan view looking on the top of the arrester and Figs. 3 and 4, are details.

This arrester is of the spark gap type, having a washer of carborundum or other insulating and non-fusible material connected to the ground terminal and metallic 25 strips with saw teeth surrounding the carborundum connected to the line wires. The novelty in the present invention consists in means for obtaining the spark gap and providing a clearance which does not vary with 30 irregularities in the size of the carborundum.

In the drawings, 11 represents the supporting member to which the porcelain base 12 of the arrester is secured by suitable 35 screws 16. 13 and 14 are the line terminals of the arrester to one of which the incoming line is attached and to the other of which the outgoing line is attached. The central terminal 15, connects to ground. This 40 terminal secures in place the carborundum washer 21 and the brass plates 22, Fig. 3, are placed on the terminals 13 and 14, by means of the slotted openings 23 and suitably secured in place by the binding screws. 45 The end of this brass plate is curved as shown to the radius of the carborundum washer 21 and provided with saw teeth. In addition two slotted openings 26, are provided in this plate for supporting the mica 50 spacer 24, Fig. 4, which has a corresponding slot 25. The mica is built up in layers according to this shape until it fits slot 26 tightly when it is driven home, the slot 26 gripping the sides of the mica and slot 25 55 of the mica gripping the sides of the brass plate 22. The outer ends of these mica

spacers, it will be noted, engage the surface of the carborundum wheel 21, Fig. 2, and thus insure that the brass strips 22 are spaced exactly at the proper sparking distance from the grounded terminal, which is a matter of the first importance in a device of this kind.

In practice it is not possible to obtain carborundum wheels or washers of the type 60 shown that are exactly of the same diameter nor is it possible to assemble these on the binding post without a certain amount of eccentricity. By the arrangement shown in this invention, the brass strips 22 are moved 65 by means of the slot 23 until the mica spacers 24 bind against the carborundum 21, thus insuring a uniform spark gap in a simple and effective manner. The use of two spacers in each strip alines the spacer 70 with the circumference of the carborundum wheel and maintains the brass plates 22 in alinement.

Having thus described my invention, I claim:

1. In a device of the class described, in combination, an incoming line terminal strip with saw teeth, an outgoing line terminal strip with saw teeth, a block of carborundum with a ground connection between 85 the saw teeth of said strips, a mica spacer supported by said strips, said spacer regulating the air gap between said strips and said carborundum block.

2. In a device of the class described, the 90 combination of an incoming line terminal having an adjustable strip with saw teeth, an outgoing line terminal having an adjustable strip with saw teeth, a grounded block of carborundum, a plurality of mica spacers 95 supported by slots in said strips, said spacers regulating the air gap between said strips and said carborundum block.

3. In a device of the class described, in combination, an incoming line terminal including a terminal strip with a slotted opening, an outgoing line terminal also including a terminal strip with a slotted opening, the ends of said strip provided with saw teeth arranged in an arc, a carborundum 100 wheel placed in the arc formed by said terminal strips, a plurality of mica spacers in each strip for regulating the air gap between said strips and said carborundum 105 wheel.

4. In a device of the class described, in combination, an incoming line terminal with

a terminal strip and an outgoing line terminal with a terminal strip, said strips having saw teeth formed in the arc of a circle, a circular wheel of carborundum placed between said strips on a grounded terminal, a plurality of mica spacers supported by each strip, said spacers engaging said carborundum wheel at different points, to regulate the air gap between said strips and said carborundum wheel.

Signed at Long Island City in the county of Queens and State of New York, this 13th day of Sept., A. D. 1920.

EDWARD ALLEN EVERETT.

Edward Allen Everett, Inventor, 10-12-20, Serial No. 1,401,596. Filed Sept. 13, 1920. Application for a patent for an improvement in a circuit breaker, consisting in a terminal strip and an outgoing line terminal with a terminal strip, said strips having saw teeth formed in the arc of a circle, a circular wheel of carborundum placed between said strips on a grounded terminal, a plurality of mica spacers supported by each strip, said spacers engaging said carborundum wheel at different points, to regulate the air gap between said strips and said carborundum wheel.
